ABSTRACT OF THE DISCLOSURE

A code dating assembly for utilization with packing machines which includes a coding wheel having removable type inserts secured therein, a backing wheel which cooperates with the coding wheel for impressing code numerals on packages and a system for synchronously driving the coding wheel to position the code numerals at the same point on package blanks is disclosed.

BACKGROUND OF THE INVENTION**Field of the invention**

This invention relates to machines for marking packages and more particularly to machines designed and adapted to impress a code on packages during the packaging operation.

Most manufacturers of consumer goods and particularly of goods which are subject to deterioration or spoilage mark the containers for such goods in a manner to permit identification of the particular batch or lot of goods, the date upon which the goods were placed on the market, or other information to permit control of such goods to prevent sale of spoiled or deteriorated goods. Conventionally, a code is worked out which is unintelligible to the public but which provides sufficient identification to the manufacturer and to those familiar with his coding system.

Description of the prior art

Code marking devices are known in the prior art. Frequently, it is necessary to install a special stage in the packaging process for encoding the packages either before or after they are filled. Such devices are often complicated and not dependable. It is an object of this invention to provide a code dating assembly for utilization in a package machine during the packaging operation.

SUMMARY

The particular objects and purposes of this invention include the provision of a novel code dating wheel which has removably received code type inserts therein. Such inserts may be individually removed and replaced to provide the desired code combination.

An additional object of the invention is the provision of a novel drive system in combination with a rotary code dating wheel for driving the code dating wheel in synchronization with a package machine transfer mechanism and conveyor to impress a code at substantially the same point on each package.

A further and important feature and object of the invention is the provision of a code dating assembly which is adapted to be pivotally swung upwardly away from the conveyor of a package machine to permit easy and free access to the package machine parts for adjustment, cleaning and repair.

The specific combinational and constructional features and details of the invention as hereinafter disclosed also comprises significant features of the invention disclosed and claimed herein.

2**BRIEF DESCRIPTION OF THE DRAWING**

FIGURE 1 is a top plan view of the code dater assembly attached to a package machine of a known and standard type.

FIGURE 2 is a longitudinal sectional view showing the code dater assembly as it would appear in operation in the packaging machine and is taken substantially along lines 2—2 of FIGURE 1 looking in the direction of the arrows.

FIGURE 3 is a transverse enlarged cross-sectional taken substantially along lines of FIGURE 2 looking in the direction of the arrows showing in detail the coding wheel and the backing wheel constructions.

FIGURE 4 is a sectional view taken substantially along lines of FIGURE 3 looking in the direction of the arrows showing the side relation of the coding wheel and the backing wheel.

**DESCRIPTION OF THE PREFERRED
EMBODIMENTS**

In the following description, two series of numerals are used. The series beginning with 100 are used to designate the packaging machine which is of a standard type manufactured by the Mead Corporation and, as such, constitutes no part of the invention in the absence of the dating assembly. The elements numbered starting with 200 specifically are part of the improvement to the package machine referred to.

With reference now to FIGURES 1 and 2 in particular, packaging machine 100 of a commercially available and standard type includes a pair of frame beams 102 and a folding assembly 104.

The packaging machine includes a main shaft 106 which is supported by two journaled end supports 108 and is rotatably driven by a sprocket 110, best shown in FIGURE 2, and a chain 112 which is drivingly interconnected with any convenient drive means such as an electric motor.

A blank transfer assembly 114 is carried on the main shaft 106 and is positioned laterally of the machine by a pair of positioning discs 116. A drive wheel 118 is secured to the shaft for rotation therewith and is held laterally between wheel positioning discs 116 and carries thereon a plurality, for example, three, outwardly extending arms 120 which in turn carry laterally adjustably extending arms 122. A plurality of vacuum cups 124 are carried on the laterally adjustable arms 122. These vacuum cups 124 rotate with the rotation of the main drive shaft 106. The vacuum is supplied through vacuum lines 126 from a vacuum manifold 128 which also rotates with the shaft. Means not shown are provided for supplying a vacuum to the manifold. This, of course, is a part of the standard machine and is not an integral part of the present invention.

A blank feed support 130 supports a plurality of package blanks 132, best shown in FIGURE 2. The transfer assembly 114 can be moved laterally and fixed in its lateral position relative to the blanks 132 by means of a bolt 134 which is secured to a rod 136 which runs laterally of the machine.

The machine also includes a pair of conveyor chain guide 138 and a pair of chains 140 guided thereby. A plurality of engaging fingers 142 are provided on the conveyor chains 140.

Operation of the machine

In operation, the material to be packaged is moved under the conveyor assembly by means not shown since this is a standard part of the commercial machine. The main drive shaft 106 rotates and carries the transfer mechanism 114 rotatably thereon. As the vacuum cups 124 rotate past and in engagement with the package blanks 132, the vacuum is applied thereby pulling one

blank from the blank feed support 130 and depositing the blank on the conveyor chain guide 138. As the conveyor chain 140 moves along the engaging fingers 142 secured thereto and protruding upwardly therefrom engage the rear edge of the package blanks 132. Each of the blanks 132, then, is moved in specific spaced relation relative to each other blank 132 along a path toward the folding assembly 104.

As the blanks 132 move toward the folding assembly 104, an upwardly turned pressure foot 144 presses them downwardly and the material to be packaged is carried upwardly to engagement with the bottom side of the blanks by a standard mechanism not shown. The folding mechanism then folds the sides of the blank 132 first downwardly and then inwardly under the material to be packaged. This folding mechanism 104 is a standard commercial component and therefore is not shown since it does not interact particularly with the dating assembly of this invention.

The code dater assembly

The code dater 200 includes a dater wheel 202 and a backing wheel 204 which are shown in greater detail in FIGURES 3 and 4 to which reference is now made.

The dater wheel includes an annular member 206 and a clamping member 208 which is secured by means of a bolt 210 and a U-clamp portion 212 to a drive means to be described.

The annular member 206 is secured by means of bolts 214 to the clamp member. The annular member includes a plurality of apertures 216 which receive type inserts 218 which carry on their outwardly extending ends desired type or symbol characters. The type inserts 218 are secured by a set screw 220 which is threadably received in a threaded aperture 222 in the annular member 206.

The backing wheel 204 includes an annular backing ring 224 which is preferably made of aluminum carried by a ball-bearing assembly 226 on a pin 228 which is, in turn, supported by a clamp 230 and bolts 232 on the distal end of an arm 234 which is secured at its proximate end by bolt 236 to a cross brace 146 of the machine. The backing wheel 204 is spaced from the clamp 230 by an annular spacer 238.

The coder wheel 202 is mounted on a shaft 240 for rotation therewith, as shown in FIGURES 3 and 4. The shaft 240, as best shown in FIGURE 1, is supported at its ends by bearings 242 which are in turn secured by bolts 244 to a pair of arms 246 which are rotatably received on main drive shaft 106 by means of bearings 248. A sprocket 250 is secured to the main drive shaft 106 and by means of a chain 252, drives the shaft 240 by means of sprocket 254.

In order to position the arms in the first position wherein the dater wheel is adjacent the backing wheel, for example, as shown in FIGURE 4, a pair of laterally inwardly extending pins 256, shown in FIGURE 1, are provided as a part of the arms. A pair of over center clamps 258 which are provided with resilient engaging tips 260 and adjustable bolts 262 bias the arms downwardly toward the backing wheel to maintain the position of the coder wheel 202 relative to the backing wheel 204.

Operation of the code dater

It will be understood that the packaging machine operates in all respects identically to the manner in which it would operate without the code dater assembly except for the additional operation of the dater assembly. Thus, when the blanks 132 are carried along the conveyor by means of fingers 142 they pass above the backing wheel 204 and below the code dater wheel 202. As shown in FIGURE 4, these wheels are positioned adjacent each other with the type inserts and the type characters extending therefrom such that the distance between the type characters and the backing wheel is less than the thickness of the package blanks. Thus, when the package

blanks are carried along the conveyor and the type numerals are in juxtaposition with the backing wheel, the type numerals will then press the numerals of characters thereon into the package. This does not destroy the printing and ornamentation on the package and, in practice, will not be seen by the customer. It is easily recognized, however, by the salesman who is familiar with the placement and nature of the code. The package blanks then pass on to the folding assembly 104 in the manner described. The position of the coding wheel 202 relative to the backing wheel 204 may be adjusted by means of bolts 262 and the resilient nature of the tip 260 and the over center nature of clamp 258 resiliently bias the code dating wheel 202 toward the backing wheel 204 to accommodate for variations in thickness of the package blanks.

It is pointed out that while in the specific embodiment the dater wheel 202 is positioned above the backing wheel 204, a reverse arrangement would be possible depending

20 on the type of machine in use. In the Mead machine, which is shown in part in the drawings, however, it is most advantageous to position the dating wheel above the backing wheel. For other machines, however, or by modifying the Mead machine, the equivalent reverse position could be used.

It will also be understood that while the machine and its operation have been described for clarity and understanding that the exact nature of the packaging machine is not an essential feature of this invention. It is necessary only that the package machine have a conveyor system and some means for transferring package blanks to the conveyor. The present invention can then be adapted to emboss the code date in the package blanks as they pass along the conveyor. Obviously, a different type of conveyor can be used also. It is therefore, the combination of a packaging machine of this general type with the code dating assembly as described herein which constitutes the essential feature of the invention.

We claim:

40 1. In combination with a packaging machine of the type which includes a feed support for package blanks, a conveyor for said blanks, and means for transferring the blanks from the support to the conveyor, the improvement further comprising:

a backing wheel rotatably mounted intermediate the ends of the conveyor such that the blanks on the conveyor will pass adjacently thereto;

45 a coding wheel;

means mounting the coding wheel adjacent the backing wheel such that the blanks on the conveyor will pass therebetween;

drive means for rotating the coding wheel synchronously with the conveyor such that substantially the same portion of each blank is compressingly engaged between said wheels to thereby impress a code symbol at substantially the same positions on each blank as it passes along the conveyor;

said packaging machine including a main drive shaft which carries the transfer means thereupon for rotation therewith and wherein the means mounting the coding wheel comprises:

a pair of substantially parallel arms rotatably secured at one end on the main drive shaft and extending therefrom;

a coder drive shaft rotatably mounted at the other ends of said arms, said coder wheel being carried thereon for rotation therewith;

a drive sprocket carried on the main drive shaft;

a driven sprocket carried on the coder drive shaft; and

a chain drivingly interconnecting said sprockets for driving the coder drive shaft in synchronization with the transfer means and the conveyor.

2. The invention of claim 1 wherein the coding wheel comprises:

an annular member having a plurality of apertures therein; and

- a plurality of individual type inserts secured in said apertures with the type carrying ends extending therefrom.
3. The invention of claim 1 further comprising: means selectively biasing said arms toward the backing wheel and for selectively releasing said arms for pivotal movement to carry the coder wheel away from the backing wheel and the conveyor to permit free access thereto.
4. The invention of claim 3 wherein the coding wheel comprises: an annular member having a plurality of apertures therein; and a plurality of individual type inserts secured in said apertures with the type carrying ends extending therefrom.
5. The invention of claim 3 wherein the biasing means comprises a pair of over-center clamps secured to said machine for selectively engaging said arms.

6. The invention of claim 5 wherein the coding wheel comprises: an annular member having a plurality of apertures therein; and a plurality of individual type inserts secured in said apertures with the type carrying ends extending therefrom.
